BALLAST CLEANING MACHINE

Application filed April 2, 1929. Serial No. 351,994.

The present invention relates to a machine for removing and handling ballast or like material of a railway track, and has particular reference to improvements in the digging means shown and described in our co-pending application for ballast cleaning machine, filed August 23, 1928, Serial No. 301,648.

In our co-pending application, a machine is shown embodying a railway car, upon which is mounted a relatively fixed or stationary plowshare which engages with the shoulder of the ballast beyond the ends or line of the cross ties. Mounted upon the car, and following the plowshare, we have shown in this application a relatively movable digger, working in conjunction with the plowshare, and adapted to dig within the ends of the cross ties, beneath the same, removing the ballast or like material, and throwing it outwardly into the trench previously formed by the plow share. The ballast or like material thus loosened up, dug, and thrown outwardly from the plowshare, is taken up by a conveyor, and may be screened or cleaned, and then returned in place between or outside the cross ties.

The present invention relates to improvements in the digging means for the ballast or like material. In accordance with our present invention, we provide a plurality of digging units, embodying relatively stationary plowshares. These plowshares are positioned different distances from the cross ties. For the purpose of illustration, we have shown three digging units, in each group, although the invention is in no sense restricted to this number. It is preferred that the plowshare of the leading unit be arranged outwardly of the ends of the cross ties, and the greatest distance from such ends, whereby this plowshare will cut the shoulder of the ballast, providing an outer trench furrow, the ballast being thrown outwardly, by the action of the plowshare and its mold board. The next rear digging unit has its plowshare positioned outwardly of the ends of the cross ties but nearer to the same and will cut further inwardly into the shoulder of the ballast or roadbed, throwing the material outwardly into the previously formed trench.

The rear or trailing digging unit has its plowshare positioned inwardly of the intermediate plowshare, and its forward end projects beneath the cross ties, and inwardly of the same for a suitable distance. The rear plowshare digs the ballast or material beneath the cross ties, inwardly from the free ends thereof, throwing the same outwardly toward the previously dug ballast or like material. Means are provided to independently raise and lower the plow-share of each unit, and to shift the plowshares laterally, inwardly or outwardly. The digging units are readily adjustable, and reliable in operation. We contemplate using the digging units in the place of the plowshare and digging mechanism shown in our said co-pending application, and all other parts of the machine may remain the same. However, the digging units are not necessarily restricted to this particular use.

In the accompanying drawings, forming a part of this specification, and in which like numerals are employed to designate like parts throughout the same,

Figure 1 is a plan view of two groups of digging units, embodying our invention.

Figure 2 is a side elevation of one group of digging units.

Figure 3 is a transverse section taken on line 3—3 of Figure 2.

Figure 4 is a horizontal section taken on line 4—4 of Figure 3.

Figure 5 is a partly diagrammatic view, showing the action of the forward plowshare,

Figure 6 is a similar view showing the action of the intermediate plowshare.

Figure 7 is a similar view showing the action of the plowshare,

Figure 8 is a plan view showing the action of the rear plowshare,

Figure 9 is a horizontal section taken on line 9—9 of Figure 5,

Figure 10 is a plan view of the point and mold board of the plowshare, and,

Figure 11 is a transverse vertical section through the shifting drum or wheel.

In the drawings, wherein for the purpose of illustration, is shown a preferred embodiment

of our invention, the numeral 15 designates the body of a railway car, mounted upon usual wheels 16, to travel upon track rails 17. These track rails are supported by the usual cross ties 18.

The digging units are designed as a whole by A, B and C. These units constitute longitudinal groups, which groups are arranged at the opposite longitudinal edges of the car body 15. The units are substantially identical and a detailed description of one will suffice for all. Each digging unit embodies a vertically arranged support 19, preferably in the form of casting including a plate 20. This plate is provided at its rear end with spaced knuckles 21, receiving therebetween knuckles 22, carried by a plate or leaf 23, having a flange or flanges 24. This plate and its flange or flanges are bolted or otherwise rigidly secured to the longitudinal edge of the car body. The knuckles 21 and 22 are pivotally connected by means of a pin 25. It is thus seen that the support 19 is pivotally connected at its rear end with the car body 15, to swing in a horizontal plane, so that its forward end may be adjusted toward or away from the car body.

Means are provided to swing the support 19 inwardly or outwardly, as stated, such means comprising a vertical shaft 26, journaled in a bearing 27, said bearing being rigidly mounted upon the car body, beneath the top of the same. At its lower end, the vertical shaft 26 carries a drum or wheel 28, rigidly mounted thereon, and this drum is provided in its top and bottom with involute grooves or tracks 29, receiving pins 30, rigidly attached to arms or brackets 31, which are rigidly secured to the inner side of the support 19. At its upper end, the shaft 26 carries a gear or pinion 32, rigidly mounted thereon, engaging a similar gear or pinion 33, which is rigidly mounted upon the lower end of a vertical shaft 34, suitably journaled in a bearing 36. The shaft 34 may be turned by a hand wheel 37, or by any other suitable means. Means are provided to lock the shaft 35 against turning movement, comprising a pinion 38, rigidly mounted thereon, and adapted for engagement with a pivoted dog 39, as shown.

The numeral 40 designates a vertically adjustable supporting element, preferably in the form of a substantially flat plate. This supporting element is provided at its longitudinal vertical edges with sockets 41, slidably receiving the edges of guides or angle irons 42, rigidly secured to vertical webs 43, integral with the plate 20. These webs are preferably reinforced by webs 44.

The means to raise and lower each supporting element 40, embodies a vertical rack 45, rigidly attached to a vertical web 46, preferably formed integral with the supporting element 40, upon the inner side thereof.

This rack is engaged by a pinion 47, carried by a horizontal transverse shaft 48, which extends into a gear casing 49. The shaft 48 is driven by a speed reducing worm drive, of any well known or preferred type, mounted in the gear casing 49, and this worm drive receives its rotation from a motor 50. The motor and gear casing 49 are suitably rigidly mounted upon the inner side of the plate 20. This may be effected by means of a platform 51, and arms 52, integral with a plate 20. It is thus seen that the motor 50 and associated elements swing as a unit with the support 19 and by driving the motor, the supporting element 41 may be vertically adjusted.

Each supporting element 41 is provided at its lower end with a plowshare or digging element 53, tapered forwardly, and a mold board 54 is rigidly attached to the supporting element with the plow share. The plow share is preferably formed separate from the mold board, and both plow share and mold board are detachably connected with the supporting element. The construction of the plowshares are substantially identical, but the rearmost plowshare is inclined inwardly toward its forward end, for a greater distance than the remaining forward plowshares.

The numeral 87 designates conveyors, disposed rearwardly of the plowshares. These are preferably the same conveyors shown in our said co-pending application.

In the operation of the machine, the supports 19 are adjusted outwardly to selected positions. The forward support is preferably adjusted outwardly beyond the intermediate support, and the intermediate support is arranged outwardly of the rear support. As a result of this, the three plowshares will be arranged different distances from the ends of the cross ties. The forward plowshare will be arranged outwardly of the ends of the cross ties, and the greatest distance from the same, the intermediate plowshare will be arranged outwardly of the ends of the cross ties and nearer to the same, while the rear plowshare will be arranged the closest to the ends of the cross ties and will project under and inwardly of the ends of the cross ties. The digging operation is effected by the slow forward travel of the car body 15. The car may be moved forwardly at about one-half of a mile an hour. The forward plowshare cuts into the shoulder *d* of the roadbed, Figure 5, outwardly of the ends of the cross ties, and at a point the farthest distance therefrom. This forms a furrow in the shoulder of the roadbed, and the ballast or like material is thrown outwardly by the action of the plowshare and mold board, forming a longitudinal hill *e*. The intermediate plowshare cuts into the shoulder *d*, nearer the ends of the cross ties, but outwardly of the same,

throwing the ballast and like material toward or into the previously formed furrow, whereby an additional hill *f* is produced. The rearmost plowshare projects under the cross ties and extends inwardly beyond the outer end thereof, for a suitable distance, and digs the ballast or like material from beneath the ends of the cross ties, throwing the same outwardly from beneath the cross ties, upon the previously formed hill *f*. The rearmost plowshare is adjusted so that it will not cut inwardly beneath the cross ties for too great an extent, thus impairing the roadbed. The hilled up ballast or like material, which has been dug or excavated from around and beneath the ends of the cross ties, and thrown outwardly beyond the same, is now collected by the conveyors 87 and may then be cleaned or screened, and finally returned to the roadbed, as fully explained in our said co-pending application.

It is to be understood that the form of our invention, herewith shown and described, is to be taken as a preferred example of the same, and that various changes in the shape, size and arrangement of parts may be resorted to without departing from the spirit of our invention, or the scope of the subjoined claims.

Having thus described our invention, we claim:—

1. In apparatus of the character described, the combination with a wheeled railway car to travel longitudinally upon a railway track, of longitudinal sets of digging devices mounted upon the car near its opposite sides, each set including a plurality of plowshares arranged to dig into the road-bed of the track and facing inwardly toward such road-bed, one plowshare being arranged to dig outwardly of the ends of the railway cross-ties and the other plowshare being arranged to dig beneath and within the ends of the cross-ties of the same road-bed, and means for holding all of the plowshares when in the operative position stationary with relation to the railway car, the arrangement being such that the digging action of all of the plowshares is due solely to their longitudinal travel with the railway car.

2. In apparatus of the character described, the combination with a wheeled railway car to travel longitudinally upon a railway track, of plowshares arranged near and upon opposite sides of the railway car and inclined inwardly with relation to the road-bed of the same railway track, said plowshares being arranged to dig beneath and within the ends of the cross-ties of the same road-bed and to conduct the loosened material outwardly from the ends of the cross-ties by virtue of their inclinations, and means for holding all of the plowshares when in the operative position stationary with relation to the railway cars, the arrangement being such that the

digging action of all of the plowshares is due solely to their longitudinal travel with the railway car.

3. In apparatus of the character described, the combination with a wheeled railway car to travel longitudinally upon a railway track, of a plurality of plowshares mounted upon the car in a longitudinal group, the plowshare in advance being arranged to dig into the road-bed of the same track outwardly of the ends of the cross-ties, and the plowshare at the rear being arranged to dig into the road-bed beneath the cross-ties and inwardly of the ends of the same, both plowshares being constructed to deflect the loosened material outwardly from the ends of the cross-ties, and means for holding all of the plowshares when in the operative position stationary with relation to the railway car, the arrangement being such that the digging action of all of the plowshares is due solely to their longitudinal travel with the railway car.

4. In apparatus of the character described, a railway car, a support pivotally mounted upon the railway car so that one end thereof may be swung laterally toward and from the car, a wheel mounted upon the car and having an involute track, a member connected with the support and engaging the involute track, means to turn the wheel, a vertically adjustable supporting element mounted upon the support, and a plowshare carried by the supporting element.

5. In apparatus for digging and removing ballast, the combination with a railway car, a plurality of separate supports mounted upon the railway car near its edge and shiftable laterally with relation thereto, separate means to shift each support whereby they are laterally adjustable independently of each other, a vertically movable supporting element carried by each support, means to vertically adjust each supporting element so that they are movable vertically independently of each other, and a plowshare carried by the lower end of each supporting element the arrangement of the plowshares being such that they all dig the roadbed of the tracks supporting the car, and one plowshare digs the roadbed at a point inwardly of the ends of the cross-ties, and the other plowshare or plowshares dig the roadbed at points outwardly of the line of digging of the plowshare digging inwardly of the ends of the cross ties.

6. In apparatus for digging up and removing ballast, the combination with a railway car, of a plurality of separate laterally movable supports mounted upon the car near its side, separate means to shift each support so that they are laterally movable independently of each other, a vertically adjustable supporting element mounted upon each support, means mounted upon the support and

movable bodily with it to raise and lower the vertically adjustable supporting element, and a plowshare carried by each supporting element, the plowshares being arranged so that 5 they all dig the side of the roadbed of a track supporting the car, one plowshare digging inwardly of the ends of the cross-ties of such track and the other plowshare or plowshares digging outwardly of the line of digging of the plowshare digging inwardly of the ends of said cross-ties.

7. In apparatus for digging up and removing ballast, the combination with a railway car, of a plurality of separate supports pivoted to the car near its side to swing horizontally with relation thereto, separate means to swing each support whereby they are independently horizontally adjustable, a vertically movable supporting element carried by each support, a motor mounted upon the horizontally swinging support to move bodily therewith, means driven by the motor to raise and lower the vertically movable supporting element, and a plowshare carried by 20 each supporting element.

8. In apparatus of the character described, the combination with a railway car to travel upon a railway track, of a longitudinal set of digging devices mounted upon the car and 30 disposed near one side thereof, each digging device including a plowshare, each plowshare being arranged to act upon the roadbed of the track carrying said car, one plowshare digging beneath and within the ends of the 35 cross-ties, and the other plowshare digging outwardly of the line of digging of the plowshare operating within the ends of the cross-ties, and means to angularly adjust each plowshare in a generally horizontal plane 40 and lock the same in the selected adjusted position to the railway car so that each plowshare is stationary with relation to the railway car, the arrangement being such that the digging action of each plowshare is due solely 45 to the longitudinal travel of such plowshare with the railway car.

9. In apparatus of the character described, the combination with a railway car to travel upon a railway track, of longitudinal sets of 50 digging devices mounted upon the car near the opposite sides of the same, each digging device embodying a plowshare, one plowshare in each set being arranged to dig beneath and within the ends of the cross-tie of 55 the track carrying the car, and the other plowshare being arranged to dig within the roadbed of the same track at a point outwardly of the line of digging of the plowshare digging inwardly of the ends of the 60 cross-ties, and means to shift each plowshare laterally with respect to the car and to lock the same to the car in a selected adjusted position so that it is stationary with relation to the car, the arrangement being such that the 65 digging action of each plowshare is due en-

tirely to its longitudinal travel with the railway car.

In testimony whereof we affix our signatures.

JOHN L. DOBBINS.
